UNITED STATES PATENT OFFICE.

FRANK M. ARNOLD, OF CLARION, PENNSYLVANIA.

SUPPORT FOR RUGS TO BE CLEANED.

1,103,019.

Specification of Letters Patent. Patented July 14, 1914.

Application filed August 9, 1913. Serial No. 783,898.

To all whom it may concern:

Be it known that I, FRANK M. ARNOLD, a citizen of the United States, residing at Clarion, in the county of Clarion and State 5 of Pennsylvania, have invented a new and useful Support for Rugs to be Cleaned; and I do hereby declare the following to be a full, clear, and exact description of the invention, such as will enable others skilled 10 in the art to which it appertains to make and use the same.

This invention relates to a new and useful support for rugs to be cleaned.

An object of the invention is to provide a 15 carpet support having longitudinally arranged carpet supporting cords to hold a rug level and stable, yet to yield incident to the blows of a carpet beater.

One of the features of the invention is the 20 provision of two rectangular frames arranged to intersect one another and pivoted at their intersection, whereby they may be arranged as shown in Figure 1, with the tie cords or ropes stretched as illustrated, there 25 being means connecting the adjacent opposite ends of said rectangular frames, whereby the tie cords may be stretched, and the tension thereof regulated.

Another feature of the invention is to 30 pivot the two rectangular frames in such wise as to permit them to collapse when not in use.

In practical fields it may be found necessary to subject the details of construction to 35 alterations, to which the patentee is entitled, provided the alterations fall within the scope of what is claimed.

The invention comprises further features and combinations of parts, as hereinafter set 40 forth, shown in the drawings and claimed.

In the drawings:—Fig. 1 is a view in perspective, showing the construction of the improved rug support. Fig. 2 is a similar view showing a rug thereon to be beaten. 45 Fig. 3 is a view showing the support collapsed, so as to be placed to one side or stored when not in use or for shipping. Fig. 4 is an enlarged detail view of one corner of one of the frames.

50 Referring more particularly to the drawings, 1 and 2 designate two rectangular

frames, arranged to intersect one another and pivoted at 3 at their intersections, by means of the bolts 4.

Each frame comprises the elongated bars 5 and the transverse bars 6, 7, and 8, screwed together as shown at 9. Under the ends of the bars 6 and screwed thereto as shown at 10 are blocks 11, in order to brace the bars 5 and 6 relative to one another. When the 15 frames are arranged as shown in Fig. 2 the bars 8 efficiently reinforce the lower opposite ends of the bars 5, which lower opposite ends constitute legs. The heads 11^a of the frames at the corners are provided with 20 screw hooks 12 to receive the rings 13, to which rings ropes 14 are connected. These ropes 14 are arranged to form a loop 15 which engage the eyes 16 of the legs of the frames. A knot 17 is formed in the end of 25 one of the strands of each loop to hold a block 18 in place, while the other strand of each loop passes through an aperture in said block. When the frames are arranged as 30 shown in Fig. 2 it will be seen that the blocks 35 may be easily adjusted, and in such wise as to regulate the tension of the tie cords or ropes 19, which are arranged longitudinally and through the eyes 20 of the bars 6 as 40 shown. These tie cords or ropes are constructed of a single length of rope, passing in and out of the eyes of the bars 6 with each end attached or fixed at 21 to one corner of 45 the head of each frame.

It will be observed that the cords or ropes 50 19 may be stretched by adjusting the blocks 18, so that the slack in said ropes will be hardly perceptible, yet as the carpet beater comes in contact with the rug the ropes will 55 yield. By arranging the frame windward, 60 the dirt and dust will pass from under the support, incident to the blows from a carpet beater.

The invention having been set forth, what 65 is claimed as new and useful is:—

In combination, a pair of rectangular 70 frames arranged to intersect one another and pivoted together at their intersection, each frame comprising a head portion including a transversely arranged bar and having a 75 series of eyes and legs formed by the side 80 bars of each frame, a single length of rope 85 90 95 100

passing back and forth through the eyes from one head to the other and arranged longitudinally with each end fixed to one end eye of each head, and adjustable rope connections between the head of each frame and the legs of the other frame whereby the first rope may be stretched.

In testimony whereof I have signed my name to this specification in the presence of two subscribing witnesses.

FRANK M. ARNOLD.
